UNITED STATES PATENT OFFICE

97,111

DESIGN FOR A TEXTILE FABRIC

Theodore S. Blum, New York, N. Y.

Application August 9, 1935, Serial No. 58,040

Term of patent 3½ years

To all whom it may concern:

Be it known that I, Theodore S. Blum, a citizen of the United States of America, residing in Manhattan, county of New York, and State of New York, have invented a new, original, and ornamental Design for a Textile Fabric, of which the following is a specification, reference being had to the accompanying drawing, forming part thereof.

The material forming the subject matter of this application is a relatively loose fabric of dark color having alternate rows of relatively wide and narrow raised stripes or bands running in one

direction and a tinsel thread running in a direction transversely of the ribs, having loops at the intersection of each rib.

Figure 1 is a face view of a section of the fabric drawn to an enlarged scale, bringing out the details of the design.

Figure 2 is a cross-sectional view of the fabric shown in Figure 1, drawn to the same scale.

I claim:

The ornamental design for a textile fabric, substantially as shown and described.

THEODORE S. BLUM.
